UNITED STATES PATENT OFFICE.

LOUIS K. SCOTFORD, OF CHICAGO, ILLINOIS, ASSIGNOR TO HILL-INDEPENDENT MANUFACTURING COMPANY, OF PHILADELPHIA, PENNSYLVANIA, A CORPORATION OF ILLINOIS.

HAND-STAMP.

1,091,394.

Specification of Letters Patent. Patented Mar. 24, 1914.

Application filed January 31, 1913. Serial No. 745,516.

To all whom it may concern:

Be it known that I, LOUIS K. SCOTFORD, a citizen of the United States of America, and a resident of Chicago, in the county of 5 Cook and State of Illinois, have invented certain new and useful Improvements in Hand-Stamps, of which the following is a specification.

This invention relates to improvements in 10 that class of hand stamps shown in my Patent No. 668,021 of February 12, 1901.

The object of the invention is to provide 15 a stamp of the character shown in said patent which will be capable of ready adjustment and which will have other advantages hereinafter described.

The invention, in its preferable embodiment, consists in the construction herein- 20 after more particularly described and illustrated and then definitely claimed.

In the drawings accompanying and forming part hereof: Figure 1 is a side elevation of a stamp made in accordance with my invention. Fig. 2 is a sectional view 25 through the line 2—2 of Fig. 1. Fig. 3 is a perspective view of the base plate and die plate, the die plate being thrown open. Fig. 4 is a perspective view of two details. Fig. 5 is a sectional detail.

30 Referring now to the details of the drawings by numerals:—1 designates the main frame of what is known as the "tumbler" form of stamp, and as usual comprises a handle 2 for depressing the yoke 3, the ends 35 of the latter having a spindle 4 connecting them and passing through the side members 5 and 6 of the frame 1, this spindle being the center on which the printing characters 8 are "tumbled" when the handle 2 is de- 40 pressed in order to move the printing characters from the inking to the printing position.

The main base plate 10 is made similar to 45 the base plate of my aforesaid Patent No. 668,021 and also on the same order as the base plate of my application Ser. No. 686,930, filed March 28, 1912, and has side arms 12 and 14 projecting therefrom, these arms being perforated as indicated at 50 15 through which the aforesaid spindle 4 passes. At the points where the spindle passes through the perforations 15 of the side arms 12 and 14, I insert a bushing 18 having a flange 20. These bushings surround the spindle 4 and the flanges 20 are lo-

cated between the side arms 12 and 14 of the movable base plate 10 and the side members 5 and 6 of the frame 1. The purpose of these flanged bushings is to prevent contact of the side arms 12 and 14 with the side members 5 and 6 of the frame 1 so that should any ink from the pad ooze down on the side arms 12 and 14, it cannot come in contact with the side members 5 and 6.

The main base plate 10 is provided with 65 the usual flanges 22 and 24 and within these flanges is pivoted the supplemental die plate 26, the latter being hinged on the pivot 28. In order to lock this supplemental die plate 26 to the main plate 10 and to cause it to 70 spring open when released I provide the following parts—the supplemental die plate 26 is provided with a grooved pointed pin 30 which, when the die plate 26 is closed against the main base plate 10, passes through a 75 perforation 32. On the under side of the main base plate, I provide a sliding catch 34 which has an opening 36 through which the pointed pin 30 enters when the supplemental plate 26 is closed against the main 80 base plate 10. Co-acting with this sliding catch 34 is a spring 38 which is firmly secured to the under side of the main base plate by means of two rivets 40 as shown in Fig. 2. A spring finger 42 is provided 85 which may be integral with said spring 38 and which co-acts with a flange 44 on the slide 34 to cause the slide 34 to co-act with the groove in the pointed pin 30 and lock the supplemental die plate 26 to the main 90 base plate 10. When it is desired to release the die plate from the base plate the operator merely has to press upon the flange 46 of the slide 34, moving said slide 34 against the tension of the spring finger 42, 95 when the slide will be moved so that the pointed pin 30 will be released from said slide 34. The supplemental die plate may now be opened upon its pivot 28.

In order to open the die plate automatically, I provide a spring 50 which passes 100 through the opening 11 in the base plate 10 and contacts with the under side of the supplemental die plate 26. This spring, in the embodiment shown, projects from the aforesaid spring 38. Thus when the supplemental die plate 26 is closed against the main base plate 10, the former strikes against the spring 50 and shoves it downward until the supplemental die plate 26 is closed against 105 110

the main base plate 10, at which time the spring finger 42 causes the sliding plate 34 to move within the groove of the pointed pin 30 and lock the supplemental die plate 26 5 to the main base plate 10. When it is desired that the die plate 26 shall move away from the main base plate 10 for the purpose of changing the position of the type 8, all the operator has to do is to shove the projection 46 on the slide 34. This, as before explained, moves the slide 34 against the tension of the spring finger 42 so that the grooved pointed pin 30 is released from the slide 34, whereupon the spring 50 forces the 15 die plate 26 outward on its pivots to the position shown in Fig. 3.

From the foregoing and accompanying drawings it will be seen that I have provided a stamp of such a construction that the 20 supplemental die plate may be opened very easily for the purpose of adjusting the type and that I have also provided a stamp wherein the side arms of the movable die plate are held away from the side members 25 of the main frame so that the ink from one cannot be transferred to the other.

What I claim as my invention is:

1. In a hand stamp, a main plate, a supplemental die plate hinged thereto, a sliding 30 latch constructed and arranged to hold said die plate to said main plate, a spring secured to said main plate and projecting through an opening therein against the die plate to force the same away from said base plate, 35 and a spring co-acting with said sliding latch to hold the latch in its locking position.

2. In a hand stamp, a main plate, a sup-

plemental die plate hinged thereto, a sliding latch secured to one of said plates and constructed and arranged to hold said plates together, a spring secured to said main plate and having a member projecting through an opening therein against the die plate to force the same away from said base plate, and a 45 spring member co-acting with said sliding latch to hold the latch in its locking position.

3. In a hand stamp, a main frame having side members, a die plate supported in said frame between said side members and having parts projecting therefrom by which the die plate is turned, and bushings carried by said projecting parts having flanges located between said projecting parts and the side members of the frame and preventing 55 said parts from contacting.

4. In a hand stamp, a main frame having side members, a die plate supported in said frame between said members and having parts projecting therefrom by which the die plate is moved from the inking to the printing position, a spindle projecting through said frame, and bushings carried by the projecting parts of said die plate, said bushings being located around said spindle and having flanges interposed between the said projecting parts of said die plate and the side members of the frame and preventing 60 said parts from contacting.

In testimony whereof I affix my signature 70 in presence of two witnesses.

LOUIS K. SCOTFORD.
